UNITED STATES PATENT OFFICE.

ISAIAH ALLISON, OF DOWNTON GROVE, AND WILLIAM J. LEIGHTY, OF CHICAGO,
ILLINOIS.

COMBINED TIE PLATE AND RAIL ANCHOR.

Application filed October 18, 1919. Serial No. 331,590.

To all whom it may concern:

Be it known that we, ISAIAH ALLISON and WILLIAM J. LEIGHTY, citizens of the United States and residents of Downers Grove, in the county of Cook, State of Illinois, and of Chicago, in the county of Cook and State of Illinois, respectively, have invented certain new and useful Improvements in Combined Tie Plates and Rail Anchors, of which the following is a description, reference being had to the accompanying drawings, which form a part of our specification.

The object of our invention is to provide a simple unitary structure adapted to function both as a tie-plate and anti-creeper or anchor, whereby suitable bearing for the rail on the ties is provided, while at the same time longitudinal movement or creeping of the rail, relative to the ties, is prevented.

Our invention also contemplates a construction which may be secured to and held in operative position on the ties by means of the usual spikes and therefore requires less operations in putting the same in place than is the case with the types of separate tie-plates and anti-creepers or anchors at present employed; our improved structure being one which will constantly remain in effective operative relation with the rail and respective ties.

Another object of our invention is to provide a structure which is adaptable to the various standard sized rails without necessitating alterations or the use of numerous sizes; the structure permitting adjustment within a comparatively wide range or latitude without in any way affecting its operative relation with the base of the rails, as will be readily apparent from the drawings and detailed description.

In the drawings—

Figure 1 is a perspective view of the preferred form of our invention.

Figure 2 is an end view of our improved tie-plate and rail anchor shown in operative position; the rail being shown, in cross-section, applied to a portion of a tie.

Figure 3 is a plan view of the construction as illustrated in Figure 2.

Figure 4 illustrates, in perspective, a portion of a railroad track, disclosing the application of our combined tie-plate and rail anchor; illustrating the usual disposition or

manner of application employed in railroad practice.

Figure 5 is a perspective view of a modified form of our combined tie-plate and rail anchor.

Figure 6 is a top plan view illustrating the application of the tie-plate and rail anchor shown in Figure 5.

In the particular exemplification of our invention as disclosed in the first four figures of the drawings, the combined tie-plate and rail anchor comprises a main body portion or flat bed plate 10, adapted to be disposed on top of the tie 11 and beneath the base of the rail 12, as shown in Figures 2 and 3; the main portion 10 being of dimensions somewhat greater than the width of the rail-base so as to extend beyond both sides of the rail when put into operative position. At a point in proximity to one of the marginal edges of the plate 10, the upper surface is provided with a shoulder or perpendicularly enlarged portion 13, adapted to be disposed parallel with and preferably in abutting relation with one side of the rail-base.

The plate 10 is provided at prearranged points with spike-receiving holes 14, adjacent to the shoulder 13; preferably a pair of holes 14 being employed at this side of the plate, arranged in alignment with the shoulder 13 as shown in Figure 1. The plate 10 adjacent the opposite longitudinal edge, is also provided with a spike-receiving hole 15, which is preferably arranged at equal distances from the forwardly and rearwardly disposed ends of the plate. The hole 15 is also preferably made somewhat larger, both transversely and lengthwise, than holes 14; and all of the holes are made somewhat larger than the usual transverse dimensions of the spikes to adapt the tie-plates to any size of commercial rail at present employed and at the same time permit of any longitudinal movement that may be necessary and allow engagement with the tie of the tie-engaging portion to be described.

The plate 10 is provided on one end with an extension 16, disposed in the plane of the main portion or plate 10 and adapted to contact with the bottom of the rail 12, see Figures 2 and 3. The lower side of the extension 16 is provided with a flange 17, see Figure 2, preferably formed integral therewith at a point in alignment with the edge

of the plate 10 and of sufficient depth to have adequate bearing on the adjacent longitudinal side of the tie 11 and thus prevent shifting of the plate transversely of the tie in a direction toward the opposite end of the plate 10. The downwardly disposed flange 17 is preferably provided with the webs or brackets 18, 18, formed integral with the flange 17 and the extension 16; thus reenforcing and bracing the tie-engaging flange or anchor 17.

It is apparent from the construction, that the webs 18, 18, and the extension 16 will prevent any lateral flexing of the tie-engaging surface or anchor 17, because extension 16 is arranged in contact with the bottom of the rail.

The extension 16 is also preferably provided with a marginal upwardly extending shoulder 19 arranged to extend parallel and in abutting relation with the base of the rail, so as to provide means whereby the plate may be welded to the rail base. With the shoulder 19 formed as shown, the welding or top face thereof may be readily filed to free it from any oxide or dirt and permit a proper welding thereof to the base of the rail 12 and lengthwise thereof, as shown at 20 in Figures 2 and 3.

With this method, the combined tie-plate and rail anchor is securely united with the rail and thus provides additional means for anchoring the rail to the tie and prevents any movement of the rail in a direction lengthwise thereof, toward the opposite side of the tie. The enlarged spike-receiving holes 14 and 15 and the position of the spikes 21, permit proper adjustment, with the contact face or portion 17 in constant abutting relation with the side of the tie; while at the same time, by autogenously welding the combined tie-plate and rail anchor to the rail, in operative contact with the ties, the rail will be securely anchored to the road-bed.

In practice the combined tie-plates and rail anchor may be arranged in any desired number and manner relative to a rail length; Figure 4 illustrating the disposition of our improved tie-plate and rail anchor at predetermined distances apart, throughout the length of the rail; with the intervening ties being provided with the ordinary tie-plates; the number of combined tie-plates and rail anchors depending upon the grades and the traffic conditions.

The combined tie-plate and rail anchor shown in Figure 1 may be cast or otherwise formed; while in Figure 5 we illustrate a tie-plate and rail anchor formed out of sheet metal.

In Figure 5 the tie-plate and rail anchor is formed from a single piece of flat steel plate to provide the main body portion or plate 22 adapted to receive the base of the

rail and be disposed on top of the tie; and this portion is shown preferably provided with two sets of spike-receiving holes 23 and 24; the holes 24 being cut transversely of the plate 22 to adapt the plate to any sized rail-base.

One end of the plate is slit or cut from opposite longitudinal sides thereof, namely what may be termed the rear end of the plate relative to the direction of traffic intended for the rail, so as to provide a partially severed lip or projection intended to be bent downwardly to provide the tie-engaging portion 25. The slits from opposite sides of the plate preferably terminate in punched holes so as to permit the proper bending of the intermediate unsevered portion as described; while the severed ends are then bent, substantially at right angles to the tie-engaging portion 25, to provide the bracing webs or brackets 26, 26. The webs 26, 26, are preferably bent so as to be disposed away from the main portion of the plate, as shown in Figure 5, thus causing one web to abut against the bottom of the rail, while the other web is disposed parallel with and adjacent to the longitudinal side of the rail-base as shown in Figure 6; and the last mentioned web,—after the plate has been spiked to the rail as shown at 27 in Figure 6,—is then welded to the side of the rail-base as shown at 28 in Figure 6.

In forming the holes 23 and 24 and placing the spikes as shown in Figure 6, the tie-plate is allowed to move forward and enables the portion 25 to establish firm contact with the side of the tie so as to constantly take care of the load or longitudinal strains applied to the rail, thereby relieving the spikes of such strains.

As is evident from the constructions, with the webs or bracket portions 18 in the form shown in Figure 1 and the webs or bracket portions 26 in the form shown in Figure 5, disposed lengthwise of the rail-base, the strains on contacting surfaces 17 and 25, respectively, will be taken care of by the webs or bracket portions, and any flexing tendency of said contact surfaces is thereby prevented, with the result that firm, rigid anchoring means are provided and the possibility of the tie-plate, and therefore also of the rails, to move transversely of the tie is prevented.

The constructions we have shown and described, we believe to be the best embodiments of the invention; but it is evident that certain modifications may be made without, however, departing from the spirit of the invention.

What we claim is:

1. A device of the class described, comprising a tie-plate adapted to varying sized rails, a downwardly disposed anchor formed integral with said plate and adapted to have

a flat bearing surface against the longitudinal side of the tie, and vertically arranged webs or brackets disposed intermediate of the tie-engaging portion and the base of the rail, with one of said webs or brackets 5 welded to the rail-base.

2. A device of the class described, comprising a tie-plate adapted to be slidably connected to the tie, the rear end of the 10 plate being provided with an integral, downwardly disposed portion adapted to bear against the longitudinal side of the tie, with a part of said portion disposed laterally beyond the side of the tie so as to bear against 15 the base of the rail.

3. A device of the class described, comprising a tie-plate adapted to varying sized rails and to be slidably connected to the tie, said plate having an end provided with a 20 tie-engaging portion or anchor adapted to be autogenously welded to the rail-base and provided with reenforcing webs.

4. A device of the character described, comprising a single piece tie-plate having a 25 rail-engaging shoulder on its upper face adjacent one end thereof, spike-receiving openings intermediate of said shoulder and the longitudinal edge of the tie-plate and adjacent to the opposite edge of the tie-plate 30 formed to permit adjustment of the tie-plate

transversely beneath the rail, one end of the tie-plate having an integral extension, coincident with said shoulder, adapted to be disposed beneath the rail in abutting relation therewith and to be welded to the adjacent edge of the rail-base. 35

5. A device of the character described, comprising a single piece tie-plate having a rail-engaging shoulder on its upper face adjacent one end thereof, spike-receiving 40 openings intermediate of said shoulder and the adjacent edge of the tie-plate and adjacent to the opposite edge of the tie-plate formed to permit adjustment of the tie-plate transversely beneath the rail, an extension integral with one end of the tie-plate, at a point, coincident with said shoulder, adapted to extend flush with the base of the rail, said extension being provided with integral webs at opposite edges connected together at one of the ends by an integral tie-engaging web whereby lateral 45 pressure of the tie against said web will be transmitted to the base of the rail.
